UNITED STATES PATENT OFFICE.

MAX ROCKSTROH, OF KLEIN-SEDLITZ, NEAR PIRNA, GERMANY.

PLATEN PRINTING-PRESS.

1,118,054.

Specification of Letters Patent. Patented Nov. 24, 1914.

Application filed June 10, 1913. Serial No. 772,845.

To all whom it may concern:

Be it known that I, MAX ROCKSTROH, a citizen of the German Empire, and residing at Klein-Sedlitz, near Pirna, Saxony, Germany, have invented certain new and useful Improvements in Platen Printing-Presses, of which the following is a specification.

My invention relates to platen printing presses, and a primary object is to provide an improved device for counterbalancing the weight of the roller carriage in such presses. To this end, I provide on the rock shaft for driving the roller carriage a toothed segment which meshes with another toothed segment which is under the influence of a spring-pressed rod mounted in the frame of the machine. A ball-bearing is arranged between the latter toothed segment and the spring-pressed rod for diminishing the friction. Devices are already well known in which the weight of the roller carriage is counterbalanced by a spring. These devices, however, comprise many pivotally connected members in order to convert the movement of the rock shaft into the stroke of the spring. Such devices are consequently complicated; they soon suffer from back lash and then work inexactly, so that they are unsuitable for the presses.

One illustrative embodiment of my invention is represented by way of example in the accompanying drawing, wherein:—

Figure 1 is a side elevation showing one form of my device, part of the frame of the press being broken away, and Fig. 2 is a horizontal section through the same.

Referring to the drawing, the roller carriage is controlled by the rod *a* which is driven by the rocking arm *b* fast on the rock shaft *c*. Fast on this shaft is the toothed segment *d* which meshes in a toothed segment *e* rotatable about the pivot *f* mounted in the frame *g* of the machine.

The toothed segment *e* has a lever-arm *h* which carries a bush *i* in which a spherical head *k* provided on the spring-pressed rod

l can lie. This rod is guided in a bracket *m* on the frame *g* and is under the action of a spring *n* coiled about it; the tension of the spring can be regulated by a nut *o*. 50

The constant pressure of the spring *n* prevents the ball *k* falling out of the bush *i*. The entire arrangement is so simple that disturbances in working, such as so frequently occur with the arrangements known heretofore comprising bolts, forks and the like, are impossible. The sole member which is subjected to material wear in the above described arrangement is the spring *n* which can be readily replaced by another 55 spring, so that the proper motion of the roller carriage is always guaranteed.

I claim:—

1. In a platen printing press, the combination with the frame, a rock shaft journaled therein, and a rocking arm fast on the shaft for controlling the roller carriage, of a toothed segment fast on the shaft, a second toothed segment journaled in the frame and meshing in the former segment, 70 and a spring-pressed rod having a spherical head constantly acting on and tending to rotate said second segment.

2. In a platen printing press, the combination with the frame, a rock shaft journaled therein, and a rocking arm fast on the shaft for controlling the roller carriage of a toothed segment fast on the shaft, a second toothed segment journaled in the frame, meshing in the former segment and 80 having a lever-arm, a bush in the lever-arm, a rod having a spherical head resting in said bush, and a spring acting on said rod and tending to hold the head thereof in said bush. 85

In testimony whereof, I affix my signature in the presence of two witnesses.

MAX ROCKSTROH.

Witnesses:

PAUL ARRAS,
CLÄRE SIMON.
